a corporation of New York

Application October 21, 1953, Serial No. 27,263

Term of patent 14 years

(Cl. D58—6)

To all whom it may concern:

Be it known that I, Abraham L. Key, a citizen of the United States, residing at New York city, in the county of Richmond and State of New York, have invented a new, original, and ornamental Design for a Bottle or Similar Article, of which the following is a specification, reference being had to the accompanying drawing, forming part thereof.

In the drawing

Fig. 1 is a front elevational view of a bottle or similar article, showing my new design;

Fig. 2 is an elevational view of the bottle looking toward a corner of the bottle;

Fig. 3 is a bottom view;

Fig. 4 is a cross-sectional view taken on the line 4—4 of Fig. 1;

Fig. 5 is a cross-sectional view taken on the line 5—5 of Fig. 1.

The sides not shown are the same as those shown.

I claim:

The ornamental design for a bottle or similar article, substantially as shown, and described.
